UNITED STATES PATENT OFFICE.

JOHN S. HALL, OF NEW YORK, N. Y.

OIL-CUP.

SPECIFICATION forming part of Letters Patent No. 427,312, dated May 6, 1890.

Application filed September 20, 1889. Serial No. 324,559. (No model.)

To all whom it may concern:

Be it known that I, JOHN S. HALL, a citizen of the United States, residing in the city, county, and State of New York, have invented 5 certain new and useful Improvements in Oil-Cups, of which the following is a full, clear, and exact description, reference being had to the accompanying drawings, forming part of this specification.

10 My invention relates to an oil-cup; and it consists in the combination of devices therein hereinafter particularly described, and as recited in the claims, whereby the advantages hereinafter specified are attained.

15 Figure 1 is an elevation of an oil-cup containing my invention. Fig. 2 is a plan of the same. Fig. 3 is a vertical central section of the same. Fig. 4 is a plan of my improved washer, hereinafter described. Fig. 5 is an 20 edge view of same, and Fig. 6 is a plan of a modified form of the washer.

A is the reservoir of the oil-cup, usually made of glass.

B is the base furnished with the threaded shank for attaching the cup to a bearing. 25 The base shown in the drawings is of the style known as "sight-feed;" but this form is not essential to my invention.

C is the top or cover of the reservoir, and is 30 usually flanged at c to fit over and inclose the rim of the reservoir, as shown. Washers or packings, as shown at c' and c'', are usually interposed between the reservoir and the base and top, respectively, and the parts are held together by a valve-tube D, which extends 35 longitudinally through the cup and through an orifice in the bottom thereof, and is screw-seated in the base and the top, as shown at d and d', respectively. The valve d'' is formed 40 on the lower end of a stem D', which extends longitudinally through the tube, and is provided with a cap or handle d' at its upper end, which is internally threaded to work on the threaded upper end d'' of the valve-tube 45 above the top C, whereby the opening and closing of the valve are accomplished. In the top or cover C is formed an orifice c'', through which the reservoir may be fed with oil or equivalent lubricant without displacing the 50 cover C.

At E is shown an arm, which is journaled at one end loosely upon the tube D, imme-

dately above the cover C, and which extends to and preferably somewhat beyond the outer edge of the cover, and is of such width as to 55 extend across and cover over the orifice c'' when it is swung over the same.

The foregoing is a description of the features of oil-cups of this class now in general use, and to which I make no claim for novelty 60 herein.

I will now describe my improvement.

E' is a washer, which fits loosely upon the valve-tube D and rests upon the hub of the arm E flatwise. Upon this washer I form a 65 perimetral lug or teat e, extending therefrom at an angle to the plane of the washer and downwardly into a recess or depression c', which I form in the top or cover C to receive it.

E'' is a binding-nut on the valve-tube immediately above the washer, and serving, when screwed down upon the washer, to hold the washer and the hub of the arm E to the cover C in position, as shown. When it is desired 70 to swing the arm E so as to uncover the orifice c'' in the cover, the washer, being held rigidly in position by its lug e, is prevented from being revolved on the tube by its frictional contact with the arm-hub, and hence 75 is prevented from revolving and loosening the nut E'', while the arm is free to move, as stated. The nut being therefore once adjusted to exert the desired pressure or binding 80 effect upon the arm-hub and washer, the arm 85 may be swung on its journal without influencing the stability of the washer and nut in their fixed position. This result is greatly to be desired in oil-cups of this description.

While the lug e serves the purpose above 90 described, it may also be made to serve as a stop to limit the movement of the arm E when it is swung to close the orifice c''. This is accomplished by forming the recess c' in the top C at such a point relatively to the location of 95 said orifice c'' as will locate the lug e, when seated in said recess, at the limit of the movement of the arm E when it has swung toward and over the orifice. This is plainly shown in Fig. 2.

The washer E' may be provided with two lugs e and e', at such a distance apart and thus seated in corresponding recesses in the top C—one on each side of the orifice c—as 100

will stop the movement of the arm E in one direction when the said arm is swung to close over the orifice and to stop the movement thereof in the opposite direction when it is 5 swung to uncover the orifice. The washer thus constructed with two lugs is shown in Fig. 6.

By means of the described devices, constructed and located relatively to each other 10 as set forth, I am enabled to provide at low cost an oil-cup in which the filling-orifice in the top of the cup may be covered and uncovered by the movement of the swinging arm E without such movement of the arm 15 disturbing the fixed position of its binding-nut and washer, and in which such movement of the arm may be limited or stopped in either or both directions.

What I claim as my invention, and desire 20 to secure by Letters Patent, is—

1. In an oil-cup, the combination, with the reservoir A, its top or cover C, provided with the orifice c^3 , the tube D, having a threaded end extending above said cover, and the arm 25 E, journaled loosely on said tube end and adapted to close said orifice, of a washer E' on said tube above said arm-hub, and having an angular perimental lug e reaching past said hub and into and seated in a recess c^4 in the 30 cover, together with a nut E^2 , working on said tube end and binding upon said washer, substantially as and for the purpose set forth.
2. In an oil-cup, the combination, with the

reservoir-cover C, provided with an orifice c^3 , and having the threaded end of tube D extending above it, of a washer E' on said tube end, provided with an angular perimental lug e , seated in a recess c^4 in the cover, and a nut E^2 , working on said tube end and binding on

said washer, together with an arm E, journaled loosely on said tube end between said washer and the cover and of such extent or width that when it is swung to close over said orifice in the cover it will abut against and its movement be limited by said washer-lug, 45 substantially as and for the purpose set forth.

3. In an oil-cup, the combination, with the reservoir-cover C, provided with an orifice c^3 and having the threaded end of tube D extending above it, of an arm E, journaled 50 loosely on said tube end and adapted to close said orifice, a washer on said tube end above said arm-hub, and having the angular perimental lugs e and e' reaching past said hub, one on each side of said arm and into corresponding recesses in the said cover and adapted in location relatively to said arm to permit the arm to play between them when swung to open or close said orifice, together with a nut E^2 on said tube end binding upon 55 said washer, substantially as and for the purpose set forth.

JOHN S. HALL.
